UNITED STATES PATENT OFFICE.

MAXWELL McGINNESS, OF LONDON, ENGLAND, ASSIGNOR TO THE RAILGRIP SYNDICATE LIMITED, OF LONDON, ENGLAND.

RAILROAD-TRACTION SYSTEM.

Application filed June 7, 1923. Serial No. 644,024.

To all whom it may concern:

Be it known that I, MAXWELL McGINNESS, a subject of the King of Great Britain, residing at 2 Gresham Buildings, Basinghall Street, London E. C. 2, England, have invented new and useful Improvements Relating to Railroad-Traction Systems, of which the following is a specification.

This invention relates to railway traction and particularly two wheels, wheel mountings, and tracks for railway vehicles and is directed to an improved system of adhesion or grip between railway vehicle wheels and the rails on which they run, the chief object being to render locomotives not entirely dependent on flat tread friction grip.

A feature of the present invention consists in obtaining what may be termed V-grip or wedge grip between the wheel rims and the rail heads and in making the grip in the nature also of a positive engagement between the contacting surfaces. This positive engagement is ensured by a rack and tooth or equivalent interengagement between the side faces of the rails and the co-operating faces of the flanges on the wheels. Instead of having actual teeth the said faces may be suitably ribbed or notched to give an equivalent effect. The teeth ribs or notches may be formed on either or both of the side faces of the rails and on either or both of the wheel flanges but preferably they are formed only on the outer face of each rail and on the outer flange of each wheel.

The toothed ribbed or notched rails may be placed throughout the track or only where great tractive force is required as at steep gradients.

The wheels having the ribbed notched or toothed flanges for engaging similarly formed side faces on the rail or rails may be the usual driving wheels of the vehicle or be supplementary thereto. In the case of a pair of supplementary wheels they may be lifted away from or pressed down onto the rail to any regulated extent by any suitable means and may be placed as a pair midway between the front and rear pairs of ordinary wheels in the case of a four wheel base.

The foregoing and other features of the present invention will now be described more fully with reference to the accompanying drawings in which:

Figure 1 is a vertical section in detail of

a wheel rim and rail head constructed and co-operating in accordance with the invention.

Figure 2 is a perspective view of the head of a piece of the rail shown in section in Figure 1.

Figure 3 is a section similar to Figure 1 showing a construction in which there is rack-grip on both side faces of the rail head.

Figure 4 is an elevation of a pair of the V-grip wedge-grip wheels on a pair of track rails.

Figure 5 is a plan view of a track and locomotive wheel base in which a pair of the improved wheels is located midway between front and rear pairs of ordinary driving wheels.

Figure 6 is a side elevation corresponding to Figure 5 showing means for raising the V-grip rack grip wheels as and when required.

Figure 7 is an end elevation showing somewhat diagrammatically a modified arrangement for obtaining a combined V-grip and rack grip effect in accordance with the invention.

Referring first more particularly to Figures 1 and 2 it is seen that the body of the wheel A has two flanges B and C which form a wedge shaped channel or rim so narrow as to exert wedge grip or so-called V-grip on the rail head D. The head of the rail is preferably shaped with sloping side faces to offer a substantial surface contact with the internal faces of the wheel flanges. Such wedge-grip between wheels and rails offers a substantially greater grip than ordinary flat tread adhesion. A still greater grip is obtained by providing for a rack and tooth inter-engagement or its equivalent. For this purpose either or each of the side faces of the rail head is toothed, ribbed or otherwise notched or indented as at E to engage corresponding formations on the co-operating internal face or faces of the flange or flanges of the wheel. As shown in Figure 1 the toothed, ribbed or notched outer flange C is preferably detachable to permit of ready replacement when worn away. It is to be observed that the base of the V-groove formed by the flanges is narrower than the width of the flat tread portion of the rail head, so that the combined wedge or V-grip and rack grip are fully effective.

In Figure 3 a rail and wheel rim

are shown in which rack grip is obtained on both faces of the rail head, and in which both flanges are detachable.

In view of the fact that a pair of V-grip 5 wheels if both fixed to a single axle could not allow for slight irregularities in the width or gauge of the track it is necessary to allow a certain amount of transverse movement of the wheels. This transverse 10 movement may be provided for by mounting the wheels on the two parts of a divided axle the adjacent ends of which are suitably housed in a connecting sleeve as shown diagrammatically at F in Figure 4. This 15 mounting of the wheel on a divided axle also permits of their being driven differentially as is especially advantageous in negotiating sharp curves in the track. Instead of an 20 actually divided axle one wheel may have an axle fitting into a sleeve serving as a hollow axle for the other wheel. Alternatively 25 each wheel can turn freely on a single axle and each be driven independently and be free to move axially to allow for track gauge variations.

The combined V-grip and rack grip wheels 30 may be used as the ordinary weight bearing wheels of the locomotive in which case provision must be made as hereinafter described for negotiating points and crossings where they occur but preferably these wheels 35 are supplementary to the ordinary driving wheels and are placed as a pair about midway between the front and rear pairs of a four wheel base as shown in Figure 5. Such wheels may be driven by chain or other driving connection with the ordinary 40 driving wheels but are preferably driven independently or differentially through differential gearing shown diagrammatically at G and change-speed gearing shown diagrammatically at H by an internal combustion engine, electric motor or steam power unit shown diagrammatically at J. If a 45 longer wheel base is required two or more such wheel assemblies may be arranged on two or more bogies.

In order to vary the degree of grip between the rails and wheels as desired, or to 50 entirely eliminate such grip if not needed, means are provided for this purpose. The axle of a pair of these wheels may for example be slung in connecting rods freely embracing one of the axles of the ordinary 55 wheels and may be normally pressed towards the rails by a spring the effect of which may be controlled by the engine driver by suitable mechanism. Such mechanism would enable the degree of grip to be 60 regulated but would not enable the wheels to be raised entirely free from the rails. In order to entirely raise the wheels any 65 convenient means may be employed such for example as the means shown diagrammatically in Figure 6. In this arrangement each

axle box K of the axle of the V-grip wheels is adapted to be raised as and when required by admitting steam or compressed air to the top of a piston L working in a cylinder M. This piston is connected by its rod N to one 70 end of a lever O which is pivoted at P to the frame or carriage of the locomotive and is attached at its other end to the spring mounting Q of the axle box K in which the axle of the supplementary wheel is housed. 75

The V-grip rack-grip wheels need be lowered only when great tractive force is required and in any event they would be raised when points and crossings are to be traversed unless the rails of such points on the 80 track are suitably cut away to permit passage of both flanges on each wheel or unless automatic wheel raising devices at such points are provided on the track. For example suitably sloping rail sections or ramps 85 alongside the track rails and rail points may be provided to engage the inner flanges of the wheels and thereby raise the wheels (as they roll) sufficiently to bring the peripheries of the outer flanges level with the top 90 of the rail heads thus enabling the wheels to travel across the rails whereupon other ramps allow them to become lowered again into V-grip engagement. For this purpose 95 the inner flanges of the wheels are preferably deeper than the outer flanges as shown in the drawings, so that even when the wheels are raised until the peripheries of their outer flanges run level with the top of the rail heads the inner flanges still engage 100 the sides of the rails and keep the wheels in alignment with the track.

Although the foregoing is a description of the preferred form in which a combination of V-grip and rack grip is obtained, 105 the invention is not limited to the particular constructions illustrated, but extends in scope to other constructions embodying the underlying features of the invention. For example instead of engaging the two side 110 faces of a rail head by two flanges on a single wheel two wheels may be employed as shown in Figure 7 set to rotate in planes angularly disposed to one another corresponding to the angle desired for the V-grip 115 and the slopes of the rail head faces. Each pair of such angularly disposed wheels is suitably mounted as in a yoke R independently of the yokes of other pairs relatively to the carriage or frame of the locomotive. 120 Each of such wheels is driven in any suitable manner the outer wheel being toothed, ribbed or notched on its tread S to engage similar formations on the outer face of the rail head, so that in this construction as in the 125 construction already described a combined wedge-grip and rack grip effect is obtained between wheels and rails.

A further modified way of bringing into 130 action a combined wedge-grip and rack-

grip effect as and when required is to employ wheels with flanges as above described but to vary the size of the rail head at different parts of the track so that on the level the wheel can run on the flat tread at the base of the V-shaped rim whereas when an incline in the track is to be traversed the head of the rail is toothed, ribbed or notched and so broad as to cause the V-shaped rim 10 of the wheel to ride up on the side faces of the rail and thereby produce the above described wedge grip and rack grip.

In all cases it will be understood that the teeth, ribs or notches on the rails do not need 15 to be cut but can be produced during the rolling of the rails at no appreciably greater cost than for the rolling of plain rails.

What I claim is:—

1. For use in a railroad traction system, a 20 locomotive comprising a body, ordinary wheels and a pair of axially movable co-axial V-grip rack-grip wheels located about midway between front and rear pairs of the ordinary wheels.

2. For use in a railroad traction system, a 25 locomotive comprising a body, ordinary wheels and a pair of V-grip rack-grip wheels located about midway between front and rear pairs of the ordinary wheels and means 30 for driving said V-grip wheels differentially.

3. In a railroad traction system, the combination with a pair of track rails each having a head with upwardly converging side 35 faces, the outer one of which is toothed, of a vehicle comprising a body and wheels thereon engaging with said track rail side faces with a V-grip rack-grip effect on each rail.

4. In a railroad traction system, the combination with a pair of track rails each having a head with upwardly converging side 40 faces the outer of which is toothed, of a vehicle comprising a body and wheels thereon each having a V-grooved rim comprising two flanges the outer of which is toothed on its rail engaging face.

5. In a railroad traction system, the combination with a pair of track rails each having a head with upwardly converging side 45 faces the outer of which is toothed, of a vehicle comprising a body and wheels thereon differentially driven and each having a V-grooved rim comprising two flanges the

outer of which is toothed on its rail engaging face.

6. In a railroad traction system, the combination with a pair of track rails each having a head with upwardly converging side 50 faces the outer of which is toothed, of a vehicle comprising a body and wheels thereon axially-movable differentially-driven and each having a V-grooved rim comprising two flanges the outer of which is toothed on its rail engaging face.

7. In a railroad traction system, the combination with a pair of track rails each having a head with upwardly converging side 55 faces the outer of which is toothed, of a vehicle comprising a body and wheels thereon arranged pairwise between front and rear pairs of ordinary wheels and each having a V-grooved rim comprising two flanges the outer of which is toothed on its rail engaging face.

8. In a railroad traction system, the combination with a pair of track rails each having a head with upwardly converging side 60 faces the outer of which is toothed, of a vehicle comprising a body and wheels thereon each having a V-grooved rim comprising two flanges the outer of which is toothed on its rail engaging face and is detachable from the wheel.

9. In a railroad traction system the combination with a pair of track rails, each having a head with upwardly converging toothed side faces, of a vehicle comprising a body and wheels thereon each having a V-grooved rim comprising two flanges each of which is toothed on its rail engaging face.

10. For use in a railroad traction system, a locomotive comprising a body, ordinary track wheels and a pair of axially movable V-grip rack-grip track wheels located about midway between front and rear pairs of the ordinary track wheels, a pair of track rails the heads of which have upwardly converging side faces toothed, notched or ribbed to engage the V-grip rack-grip locomotive track wheels, means for raising said V-grip 100 rack-grip wheels upwards from the track rails at will, and means for driving said V-grip rack-grip wheels independently of the ordinary wheels.

MAXWELL McGINNESS.
